UNITED STATES PATENT OFFICE.

JAMES WILLIAM WILLIAMS, OF SPOKANE, WASHINGTON.

ELECTRIC SIGNAL SYSTEM FOR RAILWAYS.

SPECIFICATION forming part of Letters Patent No. 718,233, dated January 13, 1903.

Application filed May 7, 1902. Serial No. 106,308. (No model.)

To all whom it may concern:

Be it known that I, JAMES WILLIAM WILLIAMS, of Spokane, in the county of Spokane and State of Washington, have invented a 5 new and useful Improvement in Electric Signal Systems for Railways, of which the following is a specification.

The invention has relation to that system of electric signaling in which the several 10 blocks or sections of the railway are combined with electric signal-circuits and connections adapted to be operated by a passing train in such manner that the said circuits shall be automatically completed and broken 15 as the train enters and leaves the successive sections or blocks to which such circuits pertain.

My invention consists of certain improvements on this kind of an electric signaling 20 system, which will first be described in connection with the accompanying drawings, forming part of this specification, and will then be more particularly pointed out in the claims.

25 In the drawings, Figure 1 is a view, mainly diagrammatic, of an electric signaling system embodying my invention. Fig. 2 is a view of one of the circuit making and breaking levers to be operated by the passing train. 30 The construction of the lever—whether C or C'—is the same. Fig. 3 is a diagrammatic representation of a system in which the successive signal-circuits overlap instead of following one another, as in Fig. 1. Fig. 4 is a diagrammatic representation of a modification in 35 which insulated track-sections are employed instead of the levers C C' of the preceding figures.

40 In Fig. 3 I have represented three overlapping signal-circuits. The connections and appliances of each circuit are the same, and I have therefore omitted these from two of the circuits as unnecessary to an understanding of the particular modification illustrated in 45 this figure.

45 In Fig. 1, which represents a single block, A B are the feed-wires, to which the several signal-circuits pertaining to the railway blocks or sections are connected, these wires 50 extending along the track and being supported on poles or otherwise, as may be found to be convenient. They are supplied with

electric current from a dynamo or other suitable source of electric energy. The railway is supposed to be a single-track railway, and it 55 therefore is equipped with two distinct sets of signal circuits and appliances, those on one side of the track being operated by trains moving in one direction and those on the other side of the track being operated by 60 trains moving in the other direction, and in this event I prefer that the signals operated by the train shall be on the left side of the track relatively to the movement of said trains, so that the engineer of that train may 65 have on his right hand, (which is the side of the cab on which he usually sits,) the signals controlled by any train moving in the opposite direction, the latter signals being thus under his more immediate observation. The signal 70 circuits and appliances are the same on both sides of the track, save that the signal-circuit-closing appliances for a train moving in one direction are at the opposite end of the block from that at which the circuit-closing appliances 75 for a train moving in the opposite direction are located. The same is also true of the circuit-opening appliances. I prefer to use electric lamps as signals, and in this event I prefer to use lamps of different colors for opposite sides of the track—say purple for one side and blue for the other—so as to prevent the engineer from confusing his lights on curves and the like with those pertaining to trains moving in an opposite direction. 80 85

Assuming there is a train moving on the track in Fig. 1 in the direction of the arrow x, the circuits and appliances on the left of the track (relatively to the direction of movement) will be affected. These devices and 90 their mode of operation are as follows: C is a hinged lever (shown in detail in Fig. 2) which (together with the mechanical parts with which it is associated) is to be inclosed in a suitable box arranged alongside of one 95 of the track-rails. It has an arm c, adapted to be struck by the wheels of the train in such way as to cause the lever C to swing or turn on its hinge. In thus turning an arm c', with which it is provided, bears upon and 100 depresses a hinged contact-arm d into contact with the stationary contact point or block e. The lever C is of course to be provided with a suitable recoil-spring (typified

at s , Fig. 2) for returning it to normal (and consequently breaking the contact between d and e) when the train ceases to act on it. It is through these instrumentalities that the 5 signal-circuit pertaining to the block is completed. The signal-circuit, or "lamp-circuit" as I shall term it, is lettered L , and it contains two electric lamps l in multiple, located one at or near opposite ends of the 10 block. The lamp-circuit is connected to the feed-wire A by wire l^1 , and it is electrically connected to the contact e by wire l^2 . From the movable contact d a wire l^3 extends to the other feed-wire B , this wire l^3 including the 15 coil or coils of a relay-magnet M . This wire l^3 , for a purpose hereinafter mentioned, is electrically connected at l^4 to the soft-iron core of the magnet. The armature-lever N and its armature n of the relay-magnet are 20 electrically connected to the wire l^2 by a branch wire l^5 around the train-controlled contacts d and e . These devices constitute what may be called an "establishing-circuit" 25 or a circuit for establishing and maintaining electrical connection between the feed-wire and the signal-circuit. When by the passing train the lever C is struck so as to bring d and e into contact, the signal-circuit L will be completed, and the lamps l therein will be 30 illuminated, the circuit at this time being from A , through l^1 and the lamps l therein in multiple $l^2 e d l^3$ and coils of relay M , to B . As soon as the train entering the block passes the lever C the circuit will be broken 35 at $d e$; but it will still remain intact, being completed by the branch l^5 from wire l^2 , the circuit thence being from said branch l^5 , through armature-lever N and armature n , (which by the previous closing of the 40 circuit through the contacts $e d$ had been closed upon the core of relay-magnet M), magnet-core m , connection l^4 , magnet-coils, wire l^3 , to feed-wire B . The lamps l will thus remain illuminated, and this condition of affairs 45 will continue until the train reaches the other end of the block. At or near the end of the block last referred to there is located a lever C' , and contacts $d' e'$ are similar in construction and operation to the parts $C d e$, 50 already described, but designed to short-circuit or cut out the magnet M , and thus break the lamp-circuit when the train leaves the block. To this end the contact d' is connected by wire l^6 to the lamp-circuit L , and 55 the contact e' is connected to the B feed-wire by a wire l^7 , and thus when the passing train moves over lever C' , and consequently depresses arm d' into contact with e' , the circuit, following the path of least resistance, will be 60 from A through l^1 , lamp-circuit L , wire l^6 , contacts $d' e'$, wire l^7 , to B . The short circuit thus established will cut out the relay-magnet M and the armature-lever N will rise, thus destroying the connection through which the 65 circuit through the relay-coils is maintained, and consequently when after the train passes the lever C rises and breaks the contact at

$d' e'$ the lamp-circuit will be broken and will remain so until another train enters the block. The train after leaving one block enters upon 70 the next block, which is provided with the same system of circuits and appliances and where the same sequence of operations as already described takes place, and so on indefinitely. It will be noted that only trains 75 which move in the direction of the arrow x will operate the levers $C C'$ on the left side of the track. Those moving in the opposite direction will depress these levers, to be sure, but in the opposite direction, where they will have no influence whatever upon their contact-arms $d d'$, and correspondingly trains moving over the track in an opposite direction to the arrow x will operatively affect only the levers $C C'$ on 80 the side of the track opposite that on which 85 are located the levers $C C'$ to be operatively affected by trains moving in the direction of arrow x . The signal-circuit to be operated and controlled by trains moving over the track from right to left is lettered L' . 90

Thus although trains may move in both directions upon the same track, yet only those circuits and appliances will be operated by the train which pertain to trains moving in the same direction with that train. It will 95 be noted that in the system thus far described the train quits one signal-section before or at the time of entering upon the next; but the signal-sections, so far as the several signal-circuits are concerned, may be overlapping, 100 the train entering upon a section and setting the signals in that section before quitting the last preceding section. This will permit the engineer of the moving train to always have a light both before and behind his train at 105 such distance as may be desired. This is exemplified in Fig. 3, where I have illustrated the overlapping system as applied to but one side of the track only, although, of course, for a single-track road it will be applied in 110 the same way, *mutatis mutandis*, to the other side of the track also. In this figure we will assume that the block typified by one lamp-circuit L is, say, four miles in length. These lamp-circuits, as will be seen, overlap each 115 other by half a length—that is to say, by the time the train has traversed half of one section it will meet the entrance-lamp of the next succeeding lamp-circuit and the appliances for establishing that circuit, so that by 120 the time the train reaches the far end of any one block and short-circuits the lamps in that block it will have, some two miles before it and behind it, the already-illuminated lamps of the next succeeding block. I have omitted 125 from the figure last referred to the mechanical details described and illustrated in the preceding figures as unnecessary and have made it almost if not wholly diagrammatic.

In the preceding figures the mechanical devices for making and breaking the signal or lamp circuits have been represented as located alongside of the track in position to be mechanically actuated by the passing train,

but in lieu of this I can make use of short insulated track-sections, the circuit connections being completed through the opposite rails of these sections and the car wheels and axle 5 by which they may be bridged. This modification is represented in Fig. 4, wherein I have represented one full block equipped for trains moving in either direction over a single track. Inasmuch as this modification requires at each end of the block an insulated track-section by which the entering train can bring into operation the signals or lamps pertaining to its side of the track, and inasmuch as the train which is quitting the block 10 must pass over this track-section, as well as the one which is entering the block, it follows that the lamps pertaining to that side of the track belonging to the entering train will be lighted by an oppositely-moving train quitting 15 the block. To remedy this, means must be provided by which the quitting train is caused to extinguish the lamps thus lighted by it. The block is of course provided at opposite ends with a lamp-circuit closer and a lamp-circuit breaker, the circuit-closer for the entering train and the circuit-breaker for the oppositely-moving or quitting train being located at the same end of the block. In addition to these two devices I provide a third 20 device at each end of the block in the nature of a circuit-breaker, by which the quitting train after having momentarily closed the lamp-circuit appropriate to the entering train is caused to break that circuit. This arrangement 25 is illustrated diagrammatically in Fig. 4. At each end of the single-track block there are three insulated track-sections T' T^2 T^3 . The inner track-section T' pertains to the circuit-closing devices of the lamp-circuit of 30 the train entering the end of the block at or near which said section is located. The middle section T^2 is a track-section by which the oppositely-moving outgoing train is caused to break the circuit which it has closed by 35 its passage over T' , and the outer section T^3 pertains to the circuit-breaking devices of the lamp-circuit appropriate to the outgoing train. In other words, the two sections T' T^3 at each end of the block in fact correspond 40 in a general way to the two levers C C' at each end of the block in the arrangements previously described. The third section T^2 is added at each end for the purpose just above indicated. L is the lamp-circuit for the trains 45 moving from left to right. L' is the lamp-circuit for the trains moving from right to left. Corresponding letters and figures of reference at the opposite ends of the block indicate corresponding parts. The relay-magnet M at each end corresponds in function to the relay-magnet already described, and, similarly, the lamp-circuit is established temporarily at first through the coils of the magnet by a direct connection from T' (the instrumentalities corresponding in this modification to the lever C in the system already described) and then permanently through the 50 coils by way of the core and armature-lever and a branch connection from the lamp-circuit. The appliances and circuit connections 70 are as follows: Considering the left-hand end of the block, the feed-wire A is connected by wire 1 to lamp-circuit L . From the latter leads a wire 2, which, by a bridge-wire 2^X , is connected to the adjoining rails t t^2 (on the same side of the track) of the two abutting insulated track-sections T' T^2 . The opposite rails t t^3 of these two sections are connected—the one, t' , by wire 3 with the coils of relay M , the other, t^3 , by a bridge-wire 5 with the adjoining rail t^5 75 of track-section T^3 —and rail t^5 is connected by wire 6 to the B feed-wire. Wire 3 is electrically connected to the core m of relay M at t^4 . From the opposite end of the coils of relay-magnet M a wire 4 leads to rail t^3 of 80 track-section T^2 . The armature-lever N and lamp-circuit are connected by a wire 7, and the rail t^4 of track-section T^2 is connected by wire 8 to the lamp-circuit L' . The circuit connections and appliances at the right-hand 85 end of the block are the same as those at the left-hand end and bear the same reference characters. If a train enters the block at the left-hand end and traverses it from left to right the sequence of operations, as 90 summing both lamp-circuits L L' to be open, will be as follows: The train first meets the outer track-section T^3 at the left-hand end of the block and passes over it without affecting any portion of the system except to momentarily excite the lamps in circuit L' . It next meets and spans the middle track-section T^2 , with the effect of momentarily establishing the lamp-circuit L , the circuit being 95 from feed-wire A through wire 1, lamp-circuit L , wire 2 2^X , rail t^2 , thence through car wheels and axle to t^3 , thence through 5 , t^5 , 6 to feed-wire B . This circuit is not through the relay-magnet M , and consequently it will be broken as soon as the train leaves section T^2 . 100 The train after passing from section T^2 meets and spans section T' . A circuit is then established as follows: from feed-wire A , through wire 1, lamp-circuit L , wires 2 2^X , rail t , through car wheels and axle to rail t' , thence 105 by wire 3 to and through coils of relay-magnet M , thence by wire 4 to rail t^3 , and thence by wire 5, rail t^5 , and wire 6, to B feed-wire. The magnet M being excited will attract its armature n , so that by the time the train 110 leaves section T' a branch will be established through wire 7 by which the lamp-circuit is maintained, the circuit then being from A , through 1, L , 7, N , n , m , t^4 , coils of magnet M , 4, t^3 , 5 , t^5 , 6, to B . The L lamp-circuit 115 thus established is maintained until the train reaches the far or right-hand end of the block, where it meets in succession the insulated track-sections T' T^2 T^3 at that end in the order named. In passing out over track-section T' it 120 establishes lamp-circuit L' through the coils of relay-magnet M appropriate to that circuit. In passing over T^2 , however, it short-circuits magnet M of lamp-circuit L' , and conse- 125 130 135

quently the latter circuit is interrupted as soon as the train travels beyond section T^3 , and in passing over the last and outermost section T^3 the train short-circuits the magnet 5 M of its own circuit L, the path of least resistance, and consequently the flow of current being from A, through 1, lamp-circuit L, 8, 1', through car wheels and axle 1 $\frac{1}{2}$, 6, to B. The magnet-relay M is thus deenergized, the 10 contact at n m is broken, with the result that when the train passes out beyond T^3 its lamp-circuit L is open. The same sequence of operations takes place in the case of a train entering the block at the right-hand end and 15 traversing it from right to left, save that in this case the signal or lamp circuit L' is established and not L. The lamp or signal circuits under this plan can be duplicated indefinitely and can be arranged, as previously described, 20 either to follow one after the other or to overlap one another.

There may be as many lamps as desired in each signal-circuit. I prefer two—one at each end of the block; but in the case of a double- 25 track road it may be necessary to have only a signal behind the train, and in that event there may be only one light, located at the entrance to the block. Signals other than electric lamps can be used; but I prefer the 30 lamps. I find that when they are suitably boxed and housed they can be seen, even in the day-time, a long distance off. In practice I propose to use for one light two or more lamps to provide against the contingency of 35 one of them burning out.

The system herein described can be applied also to switches and side tracks and will be found well adapted for use in connection with road-yards. It is also available for railway- 40 crossings to indicate the approach of a train, the lamps for this purpose being located at the crossing and being lighted when the train is within a predetermined distance of the crossing.

45 Having described my invention and the best way now known to me of carrying the same into effect, what I claim as new, and desire to secure by Letters Patent, is as follows:

1. In an electric signaling system for rail- 50 ways, the combination of main or feed wires, a signal-circuit and electrically-operated signal appliances therein, an establishing-circuit completed initially through normally open 55 contacts adapted to be temporarily closed by a passing train, a relay the coils of which are

included in the establishing-circuit and are excited when the train-controlled contacts are temporarily closed, and a branch connection around said train-controlled contacts, which 60 also includes the relay-coils and is completed through normally open contacts controlled by the relay, whereby the establishing-circuit is maintained after the opening of the train-controlled contacts, substantially as and for 65 the purposes hereinbefore set forth.

2. In an electric signaling system for rail-ways, the combination of main or feed wires, a signal-circuit and electrically-operated signal appliances therein, an establishing-circuit 70 between the feed-wires and signal-circuit completed initially through normally open contacts located at or near one end of the block and adapted to be temporarily closed by a passing train; a relay the coils of which are 75 included in the establishing-circuit and are excited when the train-controlled contacts are temporarily closed; a branch connection around said train-controlled contacts which also includes the relay-coils and is completed 80 through normally open contacts controlled by the relay, whereby the establishing-circuit is maintained through the coils of the relay-magnet after the opening of the said train-controlled contacts; and connections com- 85 pleted through normally open contacts located at or near the other end of the block and adapted to be closed temporarily by the passing train, for short-circuiting the relay-mag- 90 net, substantially as and for the purpose here- 95 inbefore set forth.

3. In an electrical block-signaling system for single-track railways having two distinct signal-circuits and electrically-operated ap- 95 pliances therein one for trains moving in one direction and the other for trains moving in the opposite direction over the block, in com- 100 bination with feed-wires and two signal-circuits L, L', of three insulated track-sections T^1 , T^2 , T^3 , at each end of the block, and con- 105 nections between the same and the feed-wires, the several signal-circuits and the elec- trical appliances therein, these parts being combined and adapted to operate substan- tially as and for the purposes hereinbefore set forth.

In testimony whereof I have hereunto set my hand this 25th day of April, 1902.

JAMES WILLIAM WILLIAMS.
